No. 613,455.

M. E. MARGESON.

Patented Nov. 1, 1898.

GATE.

(Application filed Mar. 12, 1898.)

(No Model.)

UNITED STATES PATENT OFFICE.

MANLY E. MARGESON, OF ONTARIO, INDIANA.

GATE.

SPECIFICATION forming part of Letters Patent No. 613,455, dated November 1, 1898.

Application filed March 12, 1898. Serial No. 673,633. (No model.)

To all whom it may concern:

Be it known that I, MANLY E. MARGESON, a citizen of the United States, residing at Ontario, in the county of La Grange and State of Indiana, have invented new and useful Improvements in Gates, of which the following is a specification.

My invention relates to combined sliding and swinging gates whereby the gate can be slid back to partly open the same to allow foot-passengers and stock to pass through, and which may also be swung around in the arc of a circle, so as to completely open to allow wagons and other vehicles to pass.

15 The object of the invention is to provide an improved construction of the same whereby I secure important advantages with respect to efficiency in use.

20 The invention consists in the novel construction and combination of parts hereinafter fully described and claimed.

In the accompanying drawings, Figure 1 is a side elevation of a gate constructed in accordance with my invention. Fig. 2 is a 25 transverse section of the same on the line xx , Fig. 1. Fig. 3 is a detail perspective view.

In the said drawings the reference-numeral 1 designates the front gate-post, provided with pivoted catches 2 to hold the gate in position 30 when closed.

The numeral 3 designates the rear gate-post, provided near the top and bottom with hinge members 4, each consisting of a metal rod bent at or near the center at right angles, the horizontal portion engaging with the fence-post 3, while the vertical portion engages with a plate pivoted to a plate secured to the gate-hanger hereinafter described. Said vertical portion is screw-threaded to receive a 40 retaining-nut 5.

The numeral 6 designates the gate-hanger, consisting of a triangular-shaped frame the rear vertical bar of which is provided at top and bottom with plates 7. These plates are 45 pivotally connected with plates 7^a, which are formed with several apertures, with one of which the vertical portions of the hinge members 4 engage, and thus pivotally connect the said hinges with the post 3. Journaled on

pins 9, secured to the front and rear bars of 50 said frame, are rollers 10, formed with flanges 12.

The numeral 13 designates the gate proper, comprising the horizontal rails 14 and the vertical bars or rails 15. The said rollers are 55 located between two of the rails 14, and the flanges 12 are to prevent the gate riding off the same. The said vertical rails of the triangular frame are provided with pins 17 to hold the rail engaging with the rollers down 60 upon the latter.

In practice to allow foot-passengers and stock to pass through the gateway the catch or fastener is turned to release the front end of the gate, and the latter is turned partly 65 around, when the gate can be slid back. To allow wagons or other vehicles to pass through, the gate is swung around on its hinges in the arc of a circle, so as to completely open the same. The gate can also be slid back when 70 in this position, so as to balance the same and prevent the free or front end from sagging. The gate can be opened from either side and can also be swung partly around to allow of the passage of foot-passengers with- 75 out sliding back the same, if desired.

By the peculiar construction of the hinges the hanger can be adjusted to or from the gate-post, as circumstances may require, by disengaging the vertical portions of the hinge 80 members 4 and engaging them with other holes in the plates 7^a, and each hinge is a double one, as it were, the plates 7^a being pivotally connected with both the hinge members 4 and the plates 7, which will be found 85 very advantageous in use.

Having thus fully described my invention, what I claim is—

In a combined swinging and sliding gate, the combination with the posts, the hinge members secured to one of said posts provided with upwardly-projecting screw-threaded portions, the nuts, the triangular frame provided with apertured plates, the plates formed with a series of holes or apertures pivotally connected with the said apertured plates and with the upwardly-projecting portions of the hinge members secured to the posts, the pins 90 95

secured to said frame, the flanged rollers journaled thereon and the holding-pins passing through said frames, of a gate comprising the vertical bars and the horizontal rails, one 5 of the latter of which engages with and is adapted to travel on said rollers, substantially as described.

In testimony whereof I have hereunto set my hand in presence of two subscribing witnesses.

MANLY E. MARGESON.

Witnesses:

JAMES H. HARDING,
GEORGE M. SCHAPLAND.
